UNITED STATES PATENT OFFICE.

JOHN S. McWHIRTER, OF NEW YORK, N. Y.

SEMI-STEPLESS CAR.

1,179,734.

Specification of Letters Patent. Patented Apr. 18, 1916.

Application filed January 19, 1914. Serial No. 812,935.

To all whom it may concern:

Be it known that I, JOHN S. McWHIRTER, a citizen of the United States, residing at New York, in the county and State of New York, have made a new and useful Invention in Semi-Stepless Cars, of which the following is a specification.

This invention relates to street cars, and particularly to street cars of the type wherein the passenger landing space or platform of the car is a single step distance from the ground.

The object of the invention is to provide a car of the type referred to which is simple in construction, and efficient in operation and into which ordinary cars of the usual type may be readily, easily and inexpensively converted or remodeled.

A further object of the invention is to provide means which are simple and efficient for supporting or carrying the passenger landing or platform within a single step distance from the ground, in a street car of the type referred to.

Other objects of the invention will appear more fully hereinafter.

The invention consists substantially in the construction, combination, location and relative arrangement of parts, all as will be more fully hereinafter set forth as shown in the accompanying drawings, and finally pointed out in the appended claims.

In the drawings, Figure 1 is a view in side elevation of a portion of a car of the type wherein the landing space or platform is at the end of the car, and showing such landing supported at height of a single step distance from the ground in accordance with the principles of my invention. Fig. 2 is a view in horizontal section, parts broken out, showing a floor plan of the construction shown in Fig. 1. Fig. 3 is a vertical transverse section on the line 3, 3, Fig. 2, looking in the direction of the arrows. Fig. 4 is a detail view in vertical transverse section showing the means for supporting the landing floor, Fig. 5 is a broken detail view, in side elevation, parts broken out, showing the floor structure of the landing.

The same part is designated by the same reference numeral wherever it occurs throughout the several views.

In the drawing 6, designates the body of a street car and 7, the landing space or platform therefor. The car body may be of any desired or suitable type, whether

single or double truck, prepayment or otherwise, and the landing or platform 7 may be located at any suitable point in the length of the car. While, therefore, I have shown my invention as applied to a car where the landing platform is located at the end of the car, it is to be understood that in its broadest scope, as defined in the claims, I am not to be limited or restricted in this respect.

The truck indicated generally by reference numeral 8, may be of any suitable type or standard design, and requires no special description, except that the driving wheels 9, thereof, are of reduced diameter as compared with the usual wheels employed in trucks of standard type. Thus, where the truck driving wheels are ordinarily thirty inches in diameter, I propose to employ 75 wheels of twenty-four inches diameter. The pony wheels 10 of the truck may be of the usual or ordinary size. By employing truck driving wheels of reduced diameter I am enabled to correspondingly reduce the 80 height of the floor level of the car. I have indicated the floor level of the car by dotted lines at 11, in Fig. 1, and for a portion of the length thereof I prefer to slightly incline or ramp the same, as indicated, so as 85 to bring the edge or end 12 thereof, next adjacent the landing platform 7, within an easy single step height above the floor level of the landing.

I will now describe the construction for 90 supporting the landing at a single step height above the ground.

The longitudinal side beams 13 of the under framing of the car body, have attached thereto the angle beams 14, to which 95 are bolted, the inner ends of platform supporting knees. These knees each comprise angle-bars 15, 16, with a beam 17, clamped therebetween, the angle portions of said bars being presented away from each other, as 100 clearly shown. I will designate these knee beams generally by reference numeral 18, and, in practice, I propose to employ two of such knees to support the landing platform, where the latter is located at the end 105 of the car body, one at each side of the car body. As above stated, these knees 18 are attached to the under-framing side beams 13, of the car body, and preferably at a point over or adjacent the end of the truck, 110 though in this respect my invention is not to be limited or restricted to the particular

point shown. From their points of attachment to the side beams of the car body underframing beams the knees extend, preferably in lines which converge toward each other, underneath the floor of the landing platform to form supports for the latter. The floor 11 of the car body is supported at the end thereof which terminates at the landing platform, by a transversely extending beam 20, which is secured at its ends to the frame side beams 13. In order to reduce the floor level of the landing platform to the distance of a single step height above the street level, the knee beams 18 are suitably bent or inclined, as indicated at 21, so as to enable said knees to pass underneath the car floor supporting beam 20, as most clearly shown in Fig. 1. Thus by ramping the car body floor, by employing driving truck wheels 9 of reduced diameter, and by carrying the platform or landing supporting knees beneath the car floor supporting end beam 20, I am enabled to secure a height of the landing floor of only a single easy stepping distance from the ground level, and a height of the car body floor of only a single easy stepping distance from the platform or landing floor level, and hence making what I will term a semi-stepless car.

30 The flooring 22, of the landing may be supported in any suitable manner by the knees 18. I have shown a simple construction wherein I attach angle bars or plates 23, see Fig. 3 to the knees, and upon the flanges of these angle bars I support the ends of the arched or other suitable type of floor, indicated at 24, in such relation that the upper surface of the floor arch portion 24, lies flush with the upper surfaces of the knees, as clearly shown, and over this flooring and the knees I lay the floor covering or floor proper 22.

45 If desired, and in order to afford additional support for the floor, an angle beam 25, may be placed underneath the center of the landing floor and secured to the car floor supporting beam 20, at one end, and to the end frame 26, of the landing.

50 If desired, the landing platform may be provided with doors 27, which may be controlled from any convenient point, but this is a detail to which my invention does not in any manner relate.

55 The landing platform may be inclosed by the usual vestibule framing, indicated at 28.

60 Any desired seat arrangement for the car body or for the platform or landing may be employed.

Having now set forth the objects and nature of my invention, and a construction

embracing the principles thereof, what I claim as new and useful, and of my own invention, and desire to secure by Letters Patent is:

1. A semi-stepless car including a car body having a floor, a transverse beam supporting the end of said floor, a landing or platform floor and means connected to the car body and extending beneath said transverse beam for supporting said landing or platform floor within a single step distance from the ground. 65

2. A semi-stepless car including a car body, longitudinally extending underframe side beams therefor, a transversely extending floor supporting beam, knees attached to the under-frame side beams and extending beneath and beyond said transverse floor supporting beams and a landing or platform supported by said knees within a single step distance from the ground. 75

3. A semi-stepless car including a car body, longitudinally extending underframe side beams therefor, knees secured to said side beams and extending therefrom in converging lines, and a landing or platform supported by said knees within a single step distance from the ground. 80

4. A semi-stepless car including a car body, longitudinally extending underframe side beams therefor, knees secured to said side beams and extending therefrom in converging lines, angle plates carried by said knees, and a platform or landing floor carried by said knees and plates. 85

5. A semi-stepless car including a car body, a floor therefor, longitudinally extending side beams for said body, a transversely extending floor supporting beam carried by said side beams, knees connected to said side beams and having bent portions to permit said knees to extend underneath said transverse floor supporting beam, and a landing or platform floor carried by said knees within a single step distance from the ground. 95

6. A semi-stepless car including a car body, underframe side beams therefor, angle plates carried by said side beams, knees connected to said angle plates and extending therefrom, and a platform or landing floor carried by said knee beams. 110

In testimony whereof I have hereunto set my hand in the presence of the subscribing witnesses, on this 12th day of January, 115
A. D. 1914.

JOHN S. McWHIRTER.
